UNITED STATES PATENT OFFICE.

ABRAM L. BOWER, OF BOYERTOWN, PENNSYLVANIA.

RAILWAY BLOCK-SIGNAL SYSTEM.

No. 892,652.

Specification of Letters Patent.

Patented Oct. 9, 1906.

Application filed October 22, 1902. Serial No. 123,982.

To all whom it may concern:

Be it known that I, ABRAM L. BOWER, a citizen of the United States, residing at Boyertown, in the county of Berks and State of Pennsylvania, have invented a new and useful Railway Block-Signal System, of which the following is a specification.

This invention relates more especially to an improved railway block-signal system wherein home and distant signals located along the track may be operated electrically by a moving train in a very simple and efficient way without the use of line-wires extending along the track.

15 The said invention further relates to an improved system for operating railway-signals both on the cab and at points along the track, though, as will be hereinafter seen, the cab-signals may alone be used, the track-signals alone, or both combined.

20 The principal object of this invention is to simplify and improve the railway block-signal systems as at present employed, and this I accomplish by the combinations and arrangements of circuits and apparatus herein described, and particularly pointed out in the claims.

25 The accompanying drawing is a diagram showing an arrangement of circuits and apparatus embodying my improved system applied to a double-track railroad.

Referring to the drawing, $A^2 B^2$, $A^3 B^3$, A^4 , and $A^5 B^5$ indicate the rails, respectively, of blocks Nos. 2, 3, 4, and 5 of one track of a double-track railroad, and it will be assumed that this is the track upon which run north-bound trains—that is, trains running from left to right in the drawing. The rails $B^2 B^3$, &c., will be regarded as the west rails and the rails $A^2 A^3$, &c., as the east rails. Interposed between the east rails of successive blocks are insulated rail lengths m . Separating western rails of the successive blocks are insulated rail lengths R lying opposite and similar to rail lengths m , and in addition to these are insulated rail lengths W , lying on the north side of rail lengths R . At the end of a block I locate a group of signaling devices consisting of a main relay L' , having a plurality of tongues a , b , c , f , and d , a special relay O' , a home signal $H S$, a distant signal $D S$, a polarized relay P' for controlling the distant signal, batteries E , S^2 , r , and n , all connected by circuits, as shown in the diagram and hereinafter traced. The home and distant signal devices may be of any de-

sired construction, those indicated in the drawing consisting of a movable arm acted upon by a magnet in such manner that when the magnet is energized the arm will be attracted to one position and display a certain signal, and when the magnet is not energized the arm will drop to another position and display a different signal. In the device shown the home-signal device carries a "danger-signal" and a "caution-signal," and the distant device a "safety-signal" and a "caution-signal." The specific structure of these signal devices forms no part of my present invention. A duplicate of the above group of signaling apparatus is located at the end of each block, as shown, all of the apparatus below the line of the track in the drawing being that located along the road-bed.

Each train is equipped with a set of signaling devices carried, preferably, in the cab of the locomotive and consisting, among other parts, of three signal-lamps 40 , 41 , and 42 , colored to indicate, respectively, "safety," "caution," and "danger," according to the accepted code of railway-signals, a neutral relay K , a polarized relay $P C$, operating a switch-arm h , and batteries $t s$ and $s s$. In each cab is a main operating-circuit connected to the wheels of the train and receiving current from a track-battery controlled by a distant-signal track-relay, and three branch secondary circuits in which are connected, respectively, danger, caution, and safety cab-signals. Current in the main or primary circuit operates relays K and $P C$, and these relays control the secondary cab-circuits, which operate the signals.

F^2 , F^4 , and F^6 represent engine-wheels in signaling positions in the various blocks, and F' , F^3 , and F^5 the wheels of tenders drawn by said engines, respectively. In this system the engines and tenders are insulated one from the other.

F and G represent each a pair of car-wheels in blocks 2 and 5, respectively.

In the diagram the apparatus and circuits above the line of the track are those on the trains only.

The nature of the signaling apparatus and the arrangement of circuits will be more clearly understood from the following description of the operation of the system. First, it will be assumed in describing this operation that there are two trains which affect the signaling apparatus—train F in block No. 2 and train G in block No. 5. It

will further be assumed that blocks Nos. 3 and 4 are clear at the time that engine and tender wheels F' and F² are in the position shown. The apparatus in the center above the track in the drawing is that of a train when it reaches that point. Normally—that is, when a train is not approaching the end of a block—the circuit through the coils of the special relays O' O² O³ is of such high resistance that current from track-batteries E is not sufficient to operate them. As the train G, for example, approaches the end of block No. 5 the resistance of the circuit through the coil of relay O³ is reduced, and the increase of current causes relay O³ to attract its armatures 129 and 130, partly closing the operating-circuits of the local home and distant signal devices of the apparatus between blocks Nos. 5 and 4, or that on the left in the diagram. At the same time current from track-battery E of block No. 4—that is, track-battery of the center group of devices—will traverse the coils of relay L³ and of polar relay P³, passing as follows: from the battery E through wire 123, relay O³, wire 124, contact-point 122, arm b, wire 127, rail B⁴, wire 129, relay L³, wire 158, relay P³, wire 157, rail A⁴, wire 128, arm a, contact 121, and wire 126 to the pole of the battery. This direction of current through relay P³ holds the arm c over to the right, and this closes the circuit to the distant signal on the road-bed, changing it from "caution" to "safety." The operating-circuit of this distant-signal device may be traced as follows: from battery n through wire 144, arm 129, contact 145, wire 146, relay C, wire 147, arm c, contact-point 148, and wire 149 to the battery. The relay L³, holding its armature d against stop 150, closes the operating-circuit of the home-signal device, which may be traced as follows: from battery r to armature 130 of special relay O³, magnet-coils of home-signal device H S, armature d, and contact 150 back to battery r. The home and distant signal devices on the left in the diagram acted on by currents as described both exhibit signals, the home signal indicating "caution" and the distant signal "safety." In each case the so-called "home signal" gives the signal for the block next immediately ahead, and the distant signal indicates the condition of two blocks ahead. The home and distant signals normally—that is, when not approached by a train—stand, respectively, at "danger" and "caution." This will be clear from an inspection of the central and right-hand groups of track apparatus. In each case when a train is not in an adjacent block approaching the signal-station the circuits through the signal-actuating magnets D and C will be broken at the relay-armatures 129 and 130, for the reason that there is no train in the block to which the coils of said relays are connected to complete the circuits through them—that is,

through the relays. For example, the broken circuit through the relay O² may be traced as follows: rail B⁴, wire 127, armature b, contact 122, coil of relay O², battery E, contact 121, armature a, and wire A⁴. This circuit is not completed in the present case, for there is no train in block No. 4 to complete the circuit from rail A⁴ to rail B⁴. Similarly, the broken circuit through the coil of relay O' when there is no train in block No. 3 may be traced as follows: from rail B³ to armature b, battery E, coil of relay O', armature a, and wire A³. Since there is no train in block 3 to complete the circuit from rail A³ to rail B³, the relay O' will therefore not be energized, in which case its armatures occupy the positions shown, in which they break the local circuits to the signal-operating magnets D and C. The armature f of relay L³ is connected to rail-section m, and the stop-contact 29 of said relay is connected to the rail A⁴, as shown. The relay L³ being at the present time energized, the arm f completes the electric circuit from rail-section m to rail A⁴. The armature e, also attracted by magnet of relay L³, closes the circuit to the cab-signal, which circuit may be traced as follows: from medial wire of battery S⁴, through wire 104, rail A⁵, wheels F', wire 138, contact 112, arm 111, wire 22, springs 44 45, battery s, wire 47, relay K, wire 141, relay P C, wire 23, arm 110, contact 109, wire 137, wheel F², rail M, wire 107, arm e, contact 106, wire 105, arm 135, contact 115, and wire 103 to the negative pole of battery S⁴. The current flowing in this direction through relay P C of the cab-signal apparatus causes said relay to send arm h thereof to the right and also causes relay K to attract armature i. The circuit thus completed may be traced as follows: from battery t, through wire 33, white light 42, wire 156, contact 39, arm h, wire 37, contact 31, arm i, and wire 36 to the battery. Light 42 shows that the blocks Nos. 4 and 3 are clear. The home and distant signals between blocks Nos. 4 and 3 and 2 at this time indicate "danger" and "caution," respectively, the signals displayed when the actuating-magnets of the signaling devices are not energized. This condition is brought about by causing arms 129 and 130 to maintain breaks in the exciting-circuits of said home and distant signal devices, due to the inability of the magnets of the special relay O² to attract said arms on account of the high resistance of the circuits of the track-batteries E, upon which they depend for their exciting-current. The resistances of the windings of relays L³, P³, and O² have, respectively, about four, twelve, and one-tenth ohms. Moreover, the train at F shunts and demagnetizes relays L' and P' adjacent thereto, permitting arms a b, d, f, and e of the relay L' to be drawn away. This latter act reverses the connections of the track-

battery E of the group of devices on the right, thus causing its current to flow to relay L² and polar relay P² in a direction opposite to that traced through polar relay P². The 5 poles of relay P² are therefore reversed and arm c is thrown to the left, causing the lower end 135 of said arm to engage contact 116. The track, home, and distant signals are therefore at "danger" and "caution," respectively. Assuming now that train G has passed into block No. 4, the cab-signal-operating circuits may be traced as follows: from positive pole of battery S³ through wire 114, contact 116, arm 135, wire 105, contact 106, 15 arm e, wire 107, rail m, wheel F⁴, wire 137, contact 109, arm 110, wire 23, relay P C, wire 141, relay K, wire 47, battery s, wire 143, springs 43 and 44, wire 22, arm 111, wire 138, wheel F³, rail A⁴, and wire 113 to the median 20 wire of battery S³. This direction of current draws arm h to the left and closes the local cab-circuit through the green light 41, as follows: from battery t, through wire 33, light 41, wire 160, contact 38, arm h, wire 37, contact 31, arm i, and wire 36 to the battery. This movement of the armature h also opens the circuit of the white light by breaking the contact at the stop 39. The green light in the cab, which is the caution-signal, thus 25 burns and indicates that only one block ahead is clear. When the train left block No. 5, the wheels of the engine and tender were connected through rail A⁴. This shunts the cab-circuit, and battery s s keeps the cab-relays 30 energized and the circuit supplied with feeble current, though in the same direction as that previously flowing. No break in the exciting-circuit of relay K therefore occurs, and arm i is firmly held. Thus the cab-signal is "retained." If a train should be in block 35 No. 3, approaching train in block No. 2, the battery E of block 3 would energize relay O', closing the circuits of distant signal and home signal at 129 and 130; but the train in block 40 2 short-circuits relay L', thus breaking the circuit of battery r at 132, in which case home signal is left at "danger" and the distant signal thrown to "safety." When the train reaches the end of block No. 3, the circuit to the cab is broken by arms e and f. A 45 break occurs at the first insulation, and the circuit is then closed on rail m, and then the circuit is again broken at the second insulation, arm i drops and lights the red light, which indicates "danger." The circuit is 50 as follows: from battery t, through wire 33, light 40, wire 161, contact 30, arm i, and wire 36 to the battery. When the train leaves block No. 3, the current of battery s again flows, but cannot replace arm i and disconnect the red signal. If the train remains on the signal-rails until block No. 2 is cleared, the relay L' will attract arms e and f and complete the circuit of battery S². The contact 55 30 of relay K is located so far below contact

31 that when the relay-armature i once drops the current of either of the batteries s or s s can lift it, but either is sufficient to retain it in the up position after being lifted by the stronger current from one of the track-batteries, such as S² S³. 70

What I claim is—

1. The herein-described combination of a plurality of blocks, batteries, relays, and signals connected thereto, signal-rails inserted 75 in each line of rails proper, cab-circuits containing a relay K, having an armature adapted to be controlled by the currents of battery s on the cab and battery S³ along the road-bed, battery S³ being more powerful than 80 battery s, together with home signals on the cab controlled by relay K, substantially as described.

2. In a railway signal system the combination of a series of blocks, track-circuits connected therewith, home and distant relays operated by track-circuits, home and distant signals along the road-bed controlled by those relays, insulated rails between the blocks, batteries and circuits connected thereto and controlled by the home and distant relays, a train equipped with circuits and relays, an armature operated by one of the relays, said armature being adapted to move through a wide range, an armature controlled by the other relay, together with signaling devices operated by said armatures, substantially as described. 85 90 95

3. In a railway block-signal system, a track divided into blocks insulated one from the other, signal-stations located along the track between said blocks at each of which stations is located home and distant signals, a local circuit for operating the home signal and a local circuit for operating the distant 100 signal, a home relay controlling the home-signal local circuit, and a relay controlling the distant-signal local circuit, said home and distant relays bridged across the track of the block having its commencement at the signal-station, a relay partially controlling the local circuits of both the home and distant signal device, and a main source of track-current bridged in circuit with said relay across the rails of the block having its termination at the signal-station. 105 110 115

4. In a railway block-signal system, a track divided into blocks insulated one from the other, home and distant signal relays bridged across the rails near the commencement of a block, a single source of track-current and a main-line relay bridged across the rails of said block near the end thereof, forming a normally closed track-circuit; home and distant signals located at stations between successive blocks, a local circuit for operating the home signal and a local circuit for operating the distant signal located at each of said stations, the said home and distant relays at the commencement of a block par- 120 125 130

- 5 tially controlling independently the respective local home and distant signal circuits, and the main-line relay at the end of an adjacent block partially controlling both of said local signal-circuits.
- 5 6. In a railway block-signal system, a track divided into blocks insulated one from the other, home and distant signal relays bridged across the rails near the commencement of a block, a single source of track-current and a main-line relay bridged in series across the rails near the end of said block, forming a normally closed circuit in which the resistance is sufficiently high to prevent the current therein from operating said main-line relay except when lowered by a train approaching the end of a block; home and distant signals located at stations between successive blocks, a local circuit for operating the home signal and a local circuit for operating the distant signal located at each of said stations, the said home and distant relays at the commencement of a block partially controlling independently the respective local home and distant signal circuits, and the main-line relay at the end of an adjacent block partially controlling both of said local signal-circuits.
- 10 7. In a railway block-signal system, a track divided into blocks having insulated rail-sections inserted between the rails of each block, said sections lying substantially opposite each other, additional insulated rail-sections in one side of the track, one lying adjacent to each of said insulated rail-sections on the same side of the track therewith, an incomplete electric circuit connecting the single insulated section to the adjacent track-rail at the end of a block and including in said circuit a source of current and a pole-changing device for changing the direction of the current in said circuit, an incomplete electric circuit connecting said single insulated rail-sections to the adjacent track-rail at the commencement of a block, a relay having contacts which control said circuit independently, a polar relay operating said pole-changer, a source of track-current for operating said relays, and cab-signaling apparatus operated by current from said source.
- 15 8. In a railway block-signal system, a track divided into blocks having insulated rail-sections inserted between the rails of each block, an incomplete electric circuit connecting the insulated section between blocks to the adjacent track-rail at the end of a block and including in said circuit a source of current and a pole-changing device for changing the direction of the current in said circuit, an incomplete electric circuit connecting said insulated rail-sections to the adjacent track-rail at the commencement of a block, a relay having contacts which control said circuit independently, a relay operating said pole-changer, a source of track-current for operating said relays, and cab-signaling apparatus operated by current from said source.
- 20 9. In a railway signal system, a normally incomplete main cab-signal circuit, two movable insulated contact devices carried by a train and adapted to engage the rails of said track, one of said devices connected to one leg of said main cab-circuit and the other of said devices connected to the other leg of said circuit, a cab-signal home relay connected to said main circuit, a home cab-signal and local circuit controlled by said home relay, and a switch and source of current adapted to sustain the operation of said signal along an empty block.
- 25 10. In a railway signal system, a normally incomplete main cab-signal circuit, two movable insulated contact devices carried by a train and adapted to engage the rails of the track, one of said contacting devices connected to one leg of said cab-circuit and the other of said devices connected to the other leg of said circuit, a polar relay connected in said main cab-signal circuit and adapted to be actuated by current therein, a main relay-circuit of which the tongue of said polar relay forms a part, said circuit divided at the tongue-contacts of said polar relay into two branch circuits, a signal device operated by one of said branch circuits and a second signal device operated by the other of said branch circuits.
- 30 11. In testimony whereof I have signed my name to this specification in the presence of two subscribing witnesses.
